UNITED STATES PATENT OFFICE.

JAMES W. WOODRUFF, OF BERLIN, CONNECTICUT.

DESIGN FOR A BLANK FOR TOY WIND-WHEELS.

SPECIFICATION forming part of Design No. 29,048, dated July 12, 1898.

Application filed June 21, 1898. Serial No. 684,107. Term of patent 3½ years.

To all whom it may concern:

Be it known that I, JAMES W. WOODRUFF, a citizen of the United States, residing at Berlin, county of Hartford, and State of Connecticut, have invented and produced a certain new and original Design for Blanks for Toy Wind-Wheels, fully described and represented in the following specification and the accompanying drawing, forming a part of the same.

In the accompanying drawing the figure shows the blank in plan.

The said blank is of polygonal form and is divided into sections. Each of the said sections is provided with an ornamentation consisting of a field A, bearing stars B, and a series of stripes C of varying length, the stripes in each section being arranged at an angle to the stripes in the adjoining sections.

The leading feature of the design consists in a series of sections, such as described, each section being provided with stripes arranged at an angle to the stripes of the adjoining sections, and each section being provided with a suitable field bearing stars.

Having described my invention, what I claim as new, and desire to secure by Letters Patent, is—

The design for a blank for a toy wind-wheel, substantially as herein shown and described.

In testimony whereof I have hereunto set my hand in the presence of two subscribing witnesses.

JAMES W. WOODRUFF.

Witnesses:

A. L. WOODRUFF,
JULIUS E. WOODRUFF.
